RAYMOND DINKLAGE, OF GLEN RIDGE, NEW JERSEY

ANCHORING DEVICE

Application filed September 7, 1928. Serial No. 304,479.

This invention relates to anchoring devices and has more special reference to devices for checking the creep of track rails.

The object of the present invention is to provide a simplified check which can be easily applied and removed, economically maintained in operative position and which will effectually check the creep of the rail.

One phase of the present invention resides in the provision of a single piece check which is adapted to lie flat against a tie; which has an offset portion adapted to lock with the rail base; and which can be readily removed from the rail.

Another phase of the present invention resides in the provision of a hook end adapted to be hooked over one edge of the rail base and rotated on movement of the rest of the check, the rotation of this hook end locking the check to the rail.

Heretofore anchors of the unit or one piece type were difficult to remove, requiring special appliances to get them off the rail with any degree of rapidity. The present invention affords means for permitting the rapid removal of the anchor by mere tapping or striking the anchor at appropriate points.

Other phases of the invention will become apparent from an inspection of the specification and drawings.

While one embodiment of the present invention is disclosed in the drawings, it is to be understood that the embodiment merely serves as an illustration of the underlying principles of the invention so that they may be readily comprehended by those skilled in the art and is not intended as limiting the invention to the specific form disclosed therein.

In the drawings:

Fig. 1 is a side elevation of the invention showing it as finally applied to the rail base, and Fig. 2 shows a side elevation of a check as moved to a position where it is about to be driven from the rail.

Continuing now by way of a more detailed description, a rail check or anchor indicated in its entirety by A and consisting of a single bar of somewhat resilient material is adapted to be applied to a track rail B of the conven-

tional type. One end of this check A comprises a hook shaped end C having opposed rail base engaging jaw faces C' and C'' which are spaced apart a sufficient distance to receive the edge of the rail flange, and are so arranged relatively to each other as to lock with the rail base on rotation of the hook end C. In order to accomplish the rotation of the end C and the locking of the check to the rail, the lower leg or jaw face C'' of the hook end, is carried downwardly or bent away from the rail base to form a yoke E which serves among other purposes as a lever arm to rotate the hook end C and clamp the rail edge between the jaws C' and C'' when the yoke E is carried downwardly. In order to permit the application of the check to the rail, the distance between the re-entrant portion E' of the bowed end and the contact point of jaw face C' is slightly greater than the width of the rail to allow the anchor to be initially located in the position for application to the rail. The upstanding end of the bowed portion or yoke E opposite to the rail engaging jaw C, has a latch member F with a reentrant part or a rail receiving jaw G, which is adapted to receive and seat one side of the rail base when the latch member is forced downwardly a sufficient distance, the seating of the rail base in the jaw G, locking the jaws C' and C'' in rotated position against the rail.

The inner face of the arm F is in turn inclined in the manner indicated to form a cam face H for preliminary engagement with the rail and to spring the jaw outwardly when a downward pressure is applied to the latch end as will be readily apparent from an inspection of the drawings.

In applying the check to the rail, the reentrant portion E' is first slipped over the edge of the rail base. The contact point C' is then carried over the rail base edge, the anchor then moved laterally so that the hook end C embraces the rail base, as shown; and the arm F then carried downwardly until the cam face H engages the edge of the rail. The rail engaging jaw G is then snapped into position as shown in Fig. 1 of the drawing. During the downward movement of the arm F the check rotates about the rail base engaging

point C', the jaw C" being carried upwardly and in conjunction with rail engaging point C' effectively clamping the rail base.

In order to afford means for removing the anchor the yoke E is bent or offset at J to form a temporary rail receiving shoulder on the inner face of the anchor at J' at a point close to the hook end C. By striking the anchor on the outer face of the yoke end E so as to drive the anchor laterally across the rail base in the direction of the arrow Y the rail flange edge will become seated against the shoulder J', as shown in Fig. 2. The anchor may then be removed by driving downwardly on the latch member F in the direction of the arrow X shown in Fig. 2.

Instead of the portion of the latch member which is above the rail base receiving jaw overlying and snugly fitting the rail base it is also contemplated tapering or rounding off the corner of the overhanging part so that after the anchor has been struck the rail flange will be in position to freely clear the rounded portion of the rail receiving jaw.

25 It is claimed:

1. A rail anchor for use with track rails having a hook end adapted to lock with a rail flange when the anchor is in applied position and means to hold the hook end in released position while the anchor is in applied position to permit the anchor to be freed from the rail.

30 2. A rail anchor comprising oppositely disposed rail engaging members and an auxiliary rail engaging member for temporarily receiving the anchor when it is being removed.

35 3. A rail anchor comprising a latch end and a hook end and an abutment oppositely disposed from the latch end to receive the rail flange when the latter is unseated from the hook end.

40 4. A rail anchor for use with track rails having a hook end, a downwardly projecting bar extending from the hook end, a latch end connected to the bar and a rail receiving shoulder on said bar located between the hook and latch ends.

45 5. A rail anchor for use with track rails having a hook end, a downwardly projecting bar extending from the hook end and a rail receiving shoulder on said bar for temporarily seating the rail flange when removing the anchor from the track rail.

50 6. A rail anchor formed of a single piece of material, having one face adapted to lie flat against a tie, one end fitting over the flange at one side of the rail and the opposite end having a shoulder adapted to be forced downwardly to bring said shoulder into engagement with the flange of the rail and to lock the opposite end to the rail on downward movement of the shouldered end, and means to temporarily seat the rail to release 55 the end opposite to the shouldered end so

that the latter may be driven off the rail.

7. A rail anchor comprising a hook end adapted to embrace one side of a rail and having the point of contact adapted to bear against the upper surface of the rail base located nearer to the center of the rail than the other point of contact, so that on rotation of the anchor it will rotate about the upper contact point as a center and means to temporarily hold the hook end partly off the rail. 70 75

8. A rail anchor formed of a single piece of material having one face adapted to lie flat against the tie and having one end adapted to be hooked over one side of the rail base, the hook end having a ridge adapted to abut against the rail base, and the other end having an inclined face adapted to strike the edge of the rail base, the movement of the end having the inclined face rotating the hook end of the anchor about the ridge to partly force the hook end off the rail flange. 80 85

9. A rail anchor comprising a latch member adapted to lock with one side of the track rail when said member is driven downwardly and means at the other end of the anchor to release the anchor when the latch member is driven downwardly after the anchor has locked with the rail. 90

10. A rail anchor comprising a hook end having a shoulder on which the rail edge rests when in its locked position, the portion below the shoulder being cleared away, the shoulder being adapted on rotation of the hook end to be forced past the rail base edge so that the rail base edge enters the cleared-away portion to facilitate release of the anchor. 95 100

11. A rail anchor having a hook end to engage one side of the rail and a latch end to engage the opposite side of the rail, and means to permit the anchor to be applied by driving the latch end in one direction to lock the anchor in place and to release the anchor by driving the latch end in the same direction. 105 110

Signed at New York city, in the county of New York and State of New York, this 6th day of August, A. D., 1928.
